UNITED STATES PATENT OFFICE.

GEORGE L. BENNETT, OF CLEVELAND HEIGHTS, OHIO.

SHEET WALL TILING.

Application filed March 24, 1926. Serial No. 96,918.

My invention relates to wall tiling, and more particularly to a construction thereof which will permit the mounting of sheets of tiling material upon a wall by fastening devices no part of which will be exposed within a room, or by means of devices concealed by the sheets of tiling forming the wall surface.

Heretofore I have devised a wall tiling of this character, in which the edges of adjacent sheets are fitted together by a butt joint, the fastening means being so constructed and arranged as to permit adjustment of one sheet with relation to the other to secure a sufficiently close fit between adjoining sheets to avoid the presence of a parting line between strips which will be noticeable or appreciable.

In the tiling of my invention, I provide a construction which will not only admit of the use of concealed securing means but will afford a lap joint which will not only effectively conceal the parting between adjacent strips, but will also simplify the construction of the sheets and the mounting of same with relation to the wall of a room. The fastening means employed is also so constructed as to force the sheets adjacent the vertical edges thereof tightly against the furring strips or other backing, affording a means of attachment of the sheets to the wall.

Wall tiling embodying the invention, may be quickly and accurately mounted upon a wall and, by reason of the lap joint construction, requires no particular nicety in the fitting of one sheet with relation to a sheet previously mounted adjacent thereto. It also permits the use of nails, for securing the tiling sheets in place, which nails may be driven through the tiling sheet adjacent at least one edge thereof, and in some instances adjacent both edges thereof, since the portions of the sheet adjacent this edge, or these edges, will be entirely concealed by the lap joint which may be formed either by an integral portion of one of the sheets or by a separate parting strip.

The invention consists primarily in sheet wall tiling embodying therein flat sheets, having one decorated face, adapted to be mounted against the wall; a parting strip also having a decorated face and adapted to span the gap between the edges of adjacent sheets; a slotted fitting secured to the un-

decorated face of said parting strip, and headed means adapted to be secured to the wall structure adjacent the parting and projecting beyond the face of said sheets and to enter the slot in, and engage the inner wall and the end of the slot in, said slotted fitting, whereby said parting strip is secured in relation to the wall in a position to lap and conceal the parting between adjacent sheets; and in such other novel features of construction and combination of parts as are hereinafter set forth and described, and more particularly pointed out in the claims hereto appended.

Referring to the drawings,

Fig. 1 is an elevation of a portion of the wall covered with sheet tiling embodying the invention;

Fig. 2 is a vertical section through one of the joints connecting adjacent tile sheets as shown in Fig. 1;

Fig. 3 is a horizontal section through one of said joints as shown in Fig. 1 upon an enlarged scale;

Fig. 4 is a similar view of a modified form of the invention;

Fig. 5 is a view similar to Fig. 3 of a still further modified form of the invention; and

Fig. 6 is a detail view of one of the slip fittings by means of which the parting strip is secured in position.

Like letters refer to like parts throughout the several views.

In the embodiment of the invention shown in the several views of the drawings, the studding of the building is indicated at *a* and furring strips secured thereto at *b*, this being merely an exemplification of one construction of wall in connection with which the wall tiling of my invention may be used.

Referring more particularly to the form of the invention shown in Figs. 1 to 3, I provide a plurality of flat tiling sheets *c* and *d*, one (the outer) face of which sheets is suitably decorated, or decorated and formed, in any desired manner. These sheets are mounted in relation to the furring strips *b* by means of nails *e* passing through the sheet adjacent the edge thereof and penetrating said furring strips.

In mounting these sheets, the edges of adjacent sheets are spaced slightly apart, no care being required in fitting the sheets, one in relation to another, beyond that to

ensure the sheets being properly trued up, or located, with regard to the surface decorations thereon and on adjacent sheets.

- To conceal the **parting** between adjacent sheets, I provide a channelled parting strip *f*, the outer face of which is suitably decorated, and the side flanges *f'* of which project toward the furring strips. This channelled parting strip *f* may be made separately from the main tiling sheets, or may be made integrally with one of these sheets, as will more fully appear hereinafter, this variation in construction being largely a matter of manufacturing convenience.
- 15 The parting strip *f* is secured to the wall structure by means of a slotted fitting *g* having flanges *g'* by means of which the fitting may be permanently secured within the channelled parting strip by welding or 20 other methods so as to be permanently united therewith. This fitting *g* is also channelled, and the bottom *g*² of the channel has a slot *g*³ therein and extends at an incline with relation to the side flanges *g'* so as to develop a wedging action which 25 will, as the parting strip is being brought into position, draw it toward the furring strips or other wall structure, and thus prevent the presence of any substantial crack or crevice about the edge or edges of the 30 sides of the channelled parting strip *f*. This wedging action will, through the side flanges *f'*, also force the sheets *c—d* towards the furring strips *b*.
- 35 This fitting *g* co-operates with a headed member such as an ordinary nail *h* driven into the furring strips, it being necessary however, to use care in driving these nails in order to ensure the heads of all of said 40 nails projecting substantially the same distance from said strip.

Referring now to the embodiment of the invention shown in Fig. 4, the construction is as heretofore described, excepting that the 45 parting strip *f*², corresponding with the strip *f* of Figs. 1 to 3, is made integrally with the tiling sheet *d*², a wall structure embodying the invention being composed of alternated flat tile sheets *c'* or *d'*, and tile 50 sheets *c*² or *d*² having each edge thereof provided with an integral channelled parting strip *f*².

In the embodiment of the invention shown in Fig. 5, the construction is identical 55 with that shown in Fig. 4 with the exception that a parting strip *f*³ is formed integrally with each tiling sheet *c*³ or *d*³ along one edge only of each sheet.

In all forms of the invention shown, the 60 channelled parting strip is of a depth merely sufficient to accommodate the fitting *g* and to ensure the drawing of the parting strip toward the furring strip *b* so as to close the seam or seams formed by the engagement of the top of the side or sides *f'*

of this strip against the face of the sheet at one or both sides of the parting. The parting strips whether made integrally therefrom, are of a width to not only accommodate the fitting *g*, but to extend across the line of parting between adjacent tile sheets *c—d* etc., and thus form a lap joint which will effectively conceal not only this parting line, and the means of attachment of the strip itself, but also the nails *e* used for attaching the sheet to the studding, and this condition prevails whether the parting strip is formed integrally with a sheet or as a separate strip.

The parting strips *f*, *f*² and *f*³, whether they be made separately from or integrally with a tiling sheet, should have the fittings *g* secured thereto before the exposed face of the strip is decorated. By making this strip 85 separate from the sheet, the manufacturing of the tiling is very much simplified, since the forming of the channelled strip after its decoration, may be more readily done than with a wider strip, and possible spoilage involves merely the strip itself and not the entire sheet. Hence from a manufacturing standpoint the form of the invention shown in Figs. 1 to 3, because more simple to produce, is more desirable. In the form of the 95 invention shown in Fig. 4 while the production of sheets is more difficult, the installation is somewhat simplified, because as to the form of the invention shown in Fig. 4, alternate sheets only have to be nailed in 100 position along opposite edges. In the form of the invention shown in Fig. 5, one edge only of each sheet requires to be so nailed.

In preparing a wall for mounting tiling sheets thereupon, nails *h* are driven into the furring strips *b* at the proper lateral distances as required by the width of the tiling sheets *c*, *d*, etc. In securing the furring strips to the studding *a*, it will also be necessary to locate these strips with due regard to the vertical spacing of the fittings *g* upon the tiling sheets.

In driving the nails *h* a gauge should be used, to secure approximately uniform spacing of the heads of the nails from the furring strips.

When the wall is thus prepared for the mounting of the tiling sheets, the sheets are brought against the wall and nailed in position, the nails *e* being positioned closely adjacent the edges of said sheets. Adjacent sheets have their edges spaced apart, and in order to true up the tiling sheets, the edges of the sheets may be brought against the previously driven nails *h*. If desired, however, the sheets may be first secured to the furring strips and the nails *h* later driven in a space left between the edges of such sheets.

After at least two sheets have been thus 130

secured to the wall, a parting strip *f* is positioned with relation to the line of parting between adjacent sheets, with the slots in the fittings *g* astride the vertical line of 5 nails *h* with which these fittings are respectively adapted to co-operate, and the strip forced downwardly. The inclined bottom *g²* of the fitting will draw the strip *f* toward the furring strips *b* and the sheets 10 *c-d*, and thus close the side flanges *f'* of said strip upon the tiling sheets, and form a tight joint between these sheets and the parting strips.

Above I have referred to the practice of 15 mounting tiling sheets and their parting strips when the construction of same is as shown in Figs. 1 to 3 of the drawings.

When the construction is as shown in Fig. 20 4 of the drawings, alternate flat sheets *c'* are nailed upon the furring strips by means of nails *e* along opposite edges of each sheet. Nails *h* are then driven into the furring strips in a manner heretofore described and 25 a section *d'* with an integral parting strip at each edge thereof, each parting strip having its fittings *g*, is mounted in the same manner as when a separate parting strip is used, and with the same results.

In the form of the invention shown in Fig. 30 5, a tiling sheet is mounted upon the wall by means of nails *e* along one (the flat) edge of the sheet. When a sheet is thus properly positioned, nails *h* are driven adjacent this flat edge into the furring strip and the adjacent sheet is mounted first by engaging the integrally formed parting strip *f²* along one edge thereof with the line of nails *h*, and then by nails passing through the flat 35 edge of the sheet, succeeding sheets being mounted in like manner.

In the forms of the invention shown in Figs. 4 and 5, where the parting strip is made integrally with the tiling sheet, care should be exercised in the forming of the 45 parting strip *f²* so that the outer flange *f'* thereof will be of a height to properly engage the flat surface of an adjacent tiling sheet.

In all forms of the invention, nails are 50 used for securing the tiling sheet in position, and whether these nails extend along one or both of the edges of the tiling sheet, the parting strip will effectively conceal them. Furthermore, the line of parting between a 55 parting strip and a flat portion of an adjacent tiling sheet, will be parallel with the plane of the wall or of the tiling sheets, and also will be in a bead so as not to be noticeable from almost any angle. The wedging 60 action secured by the fittings *g* will close the flange or flanges *f'* sufficiently tightly against the tiling sheets, however, to secure a joint at the parting sufficiently tight to be practically invisible under all conditions.

65 The tiling sheets themselves while of light

weight sheet stock, will nevertheless possess considerable inherent rigidity when mounted upon a wall, and there will be no buckling of these sheets resulting from the pressure thereon by the parting strips, since this 70 pressure will be toward the furring strips against which the sheets lie perfectly flat.

It is not my intention to limit the invention to the precise details of construction shown in the accompanying drawings, it being apparent that such may be varied without departing from the spirit and scope of the invention.

Having described the invention, what I claim as new and desire to have protected 80 by Letters Patent, is:—

1. Sheet wall tiling embodying therein flat sheets, having one decorated face, adapted to be mounted against the wall; a channelled parting strip also having a decorated face and adapted to span the gap between the edges of adjacent sheets, a slotted fitting secured to the undecorated face of said parting strip; and headed means adapted to be secured to the wall structure adjacent the parting and projecting beyond the face of said sheets and to enter the slot in, and engage the inner wall and the end of the slot in, said slotted fitting, whereby said parting strip is secured in relation to the wall in a 90 position to lap and conceal the parting between adjacent sheets.

2. Sheet wall tiling embodying therein flat sheets, having one decorated face, adapted to be mounted against the wall; a channelled parting strip also having a decorated face and adapted to span the gap between the edges of adjacent sheets; a channelled fitting secured at its edges to the undecorated face of said parting strip, the bottom of said 100 fitting extending at an incline to the edges thereof and having a slot therein whereby when engaged with a co-operating member secured to the wall, movement of said fitting will develop a wedging action towards the wall, and headed means adapted to be secured to the wall structure adjacent the parting and projecting beyond the face of said sheets and to enter the slot in, and engage the inner wall and the end of the slot in, said 110 channelled fitting, whereby said parting strip is secured in relation to the wall in a position to lap and conceal the parting between adjacent sheets.

3. Sheet wall tiling embodying therein flat sheets, having one decorated face, adapted to be mounted against the wall; a channelled parting strip also having a decorated face and being of a width to span the gap at the parting between adjacent sheets, and bring the side flanges thereof against the decorated face of such sheets at a point to conceal nails used for securing said sheets in position, a slotted fitting secured to the undecorated face of said parting strip, and headed means 120

adapted to be secured to the wall structure adjacent the parting and projecting beyond the face of said sheets and to enter the slot in, and engage the inner wall and the end of the slot in, said slotted fitting, whereby said parting strip is secured in relation to the wall in a position to lap and conceal the parting between adjacent sheets.

4. Sheet wall tiling embodying therein flat sheets, having one decorated face, adapted to be mounted against the wall; a channelled parting strip also having a decorated face and being of a width to span the gap at the parting between adjacent sheets, and bring the side flanges thereof against the decorated face of such sheets at a point to conceal nails used for securing said sheets in position; a channelled fitting secured at its edges to the undecorated face of said parting strip, the bottom of said fitting extending at an incline to the edges thereof and having a slot therein whereby when engaged with a co-operating member secured to the wall, movement of said fitting will develop a wedging action towards the wall, and headed means adapted to be secured to the wall structure adjacent the parting and projecting beyond the face of said sheets and to enter the slot in, and engage the inner wall and the end of the slot in, said channelled fitting, whereby said parting strip is secured in relation to the wall in a position to lap and conceal the parting between adjacent sheets.

5. Sheet wall tiling embodying therein flat sheets having one decorated face adapted to be mounted against the wall, a channelled parting strip also having a decorated face and adapted to span the gap between the edges of adjacent sheets, a plurality of vertically alined spaced slotted fittings secured

to the undecorated face of said parting strip, and headed means adapted to be secured to the wall structure adjacent the parting and projecting beyond the face of said sheets and to enter the slot in, and engage the inner wall and the end of the slot in, said slotted fittings respectively, whereby said parting strip is secured in relation to the wall in a position to lap and conceal the parting between adjacent sheets.

6. Metallic wall tiling embodying therein flat metal sheets having one decorated face adapted to be mounted against the wall, a channelled parting strip also having a decorated face and being of a width to span the gap at the parting between adjacent sheets, and bring the side flanges thereof against the decorated face of such sheets at a point to conceal nails used for securing said sheets in position, a plurality of vertically alined spaced channelled fittings, each of said fittings being secured at its edges to the undecorated face of said parting strip, the bottom of each of said fittings extending at an incline to the edges thereof and having a slot therein whereby when engaged with a co-operating member secured to the wall, movement of said fittings will develop a wedging action towards the wall, and headed means adapted to be secured to the wall structure adjacent the parting and projecting beyond the face of said sheets and to enter the slot in, and engage the inner wall and the end of the slot in, said channelled fittings, whereby said parting strip is secured in relation to the wall in a position to lap and conceal the parting between adjacent sheets.

In witness whereof I have hereunto affixed my signature, this 18th day of March, 1926.

GEORGE L. BENNETT.
